UNITED STATES PATENT OFFICE.

JOSEPH T. VARNEY, OF SOUTH WAREHAM, ASSIGNOR OF ONE-FOURTH TO
EDGAR ROBINSON, OF WAREHAM, MASSACHUSETTS.

MOP AND SCRUBBING-BRUSH HOLDER.

SPECIFICATION forming part of Letters Patent No. 399,223, dated March 5, 1889.

Application filed August 2, 1888. Serial No. 281,766. (No model.)

To all whom it may concern:

Be it known that I, JOSEPH T. VARNEY, a citizen of the United States, residing at South Wareham, in the county of Plymouth and State of Massachusetts, have invented a new and useful Improvement in a Combined Mop and Scrubbing-Brush Holder, of which the following is a specification.

My invention is a combined mop and scrubbing-brush holder; and it consists in certain novel features hereinafter described and claimed.

In the accompanying drawings, Figure 1 is a perspective view of my improved device, showing a mop and a scrubbing-brush secured thereto, and Fig. 2 is a perspective view of the holder free of the mop and scrubbing-brush.

My improved holder is a casting comprising the plate A, having the parallel flanges B depending from its side edges and provided with internally-threaded horizontal openings, in which one or more clamping-screws, C, may be mounted and adapted to bind against the sides of the brush to secure the same within the holder. The plate A is further provided at its corners with vertical internally-threaded openings, in which are mounted vertical screws or bolts D, as shown, which pass through the ends of a clamping-bar, E, and are adapted to secure the same firmly on the mop.

In practice the head of the brush is placed between the flanges depending from the plate A, and the clamping-screws turned up against the sides of the same to secure it in the holder. The mop is secured in position by having one end inserted between the plate A and the horizontal clamping-bar, and the vertical screws or bolts are then turned down-

ward to cause the said bar to bind upon the 40 mop, thereby firmly securing it. The plate is provided on its upper side with an integral inclined socket, F, in which the end of the handle G is secured, as will be readily understood.

It will thus be seen that I have provided an extremely simple device, by means of which the mop and brush may be secured to a single device, to be used alternately, or either may be secured thereto without the other. In 50 ease of damage to either the mop or the brush, it can be easily removed and a new one substituted therefor.

The device is very cheap and simple, and its efficiency is thought to be obvious.

Having thus described my invention, what I claim, and desire to secure by Letters Patent, is—

1. A combined mop and brush holder, comprising a plate having depending flanges at 60 its edges, binding-screws mounted in said flanges to secure the brush, and a clamping-bar mounted on the upper side of the plate to secure the mop, as set forth.

2. A combined mop and brush holder, comprising a plate having depending flanges at 65 its edges, binding-screws mounted in said flanges to secure the brush, vertical screws on the upper side of the plate, and a clamping-bar on the said screws to secure the mop, as 70 set forth.

In testimony that I claim the foregoing as my own I have hereto affixed my signature in presence of two witnesses.

JOSEPH T. VARNEY.
